COMPRESSOR

Carl W. Albertson, Chicago, Ill.

Application December 19, 1936, Serial No. 116,758

4 Claims. (Cl. 230—138)

This invention relates to compressors, and particularly to rotary compressors used for refrigeration.

The principal object of the invention is to provide an improved compressor in which gas under head pressure is admitted to both sides of the compressor immediately after the compressor stops, so that the same may start again under substantially no-load conditions.

10 Other objects, advantages and capabilities of the invention will appear from the following description of a preferred embodiment thereof, taken in conjunction with the accompanying drawings, in which:

15 Fig. 1 is a longitudinal section through a compressor embodying my invention and associated parts of a refrigerating machine;

Fig. 2 is an end elevation of the compressor, the discharge pressure casing being removed;

20 Fig. 3 is a sectional elevation taken through the compressor on the line 3—3 of Fig. 1;

Fig. 4 is a sectional plan view through the compressor, taken on the line 4—4 of Fig. 2, and

25 Fig. 5 is a sectional detail view, taken on the line 5—5 of Fig. 2.

Referring to the drawings, the invention is illustrated therein as applied to the compressor of the condenser-compressor unit described and claimed in my copending application Serial No. 30 68,188 filed March 11, 1936. This compressor comprises two end plates 10 and 11 and an intermediate plate 12 secured therebetween. A cylinder 13 is formed in the intermediate plate 12 and the end plates 10 and 11 provide bearings 14 and 15 in alignment therewith. A shaft 16 is rotatably mounted in said bearings and this shaft has an enlarged eccentric member 17 located within the cylinder 13. Upon the eccentric member is mounted an impeller ring 18 which has rigidly secured thereto a radial vane 19 which is adapted to slide between blocks 20 located in a cylindrical opening 21 in the plate 12. The outer end of the vane 19 is in free communication with an opening 22 in the plate 12, 40 which opening communicates through an opening 23 in the plate 10 to the lower portion of the discharge pressure chamber 24. The chamber 24 is mounted on the plate 11 so as to enclose the plates 10 and 12.

50 The shaft 16 extends through the plate 11, the portion therebeyond being reduced as shown at 25 and being attached to a coupling member 26 whereby it may be flexibly coupled to the shaft 27 of an electric motor. The plate 11 is provided 55 with a boss which provides an annular chamber

28 for the reception of a counterbalance weight 29 rigidly secured on the shaft 16. The chamber 28 is closed by an outer plate 30. A metal bellows 30 is secured to the coupling member 26 and to an annular member 31 which has a reduced annular bearing portion abutting against the plate 30. The annular member 31 is forcibly pressed against the plate 30 by a spring 32 which also abuts against the coupling member 26.

The bearing 14 in the end plate 10 is closed 10 by a plug 33 which is in spaced relation to the adjacent end of the shaft 16 so as to provide a lubricant chamber 34. The shaft 16 has an axial bore 35 and a communicating radial opening 36 which establish communication between the 15 chamber 34 and the chamber 28 and the metal bellows 30. The chamber 28 communicates with the suction side of the chamber 13 by means of a port 38. This port is arranged so that it is opened and closed by the annular impeller 18 20 during each revolution of the shaft 16.

The radial vane 19 is provided with a longitudinal duct 37 which is in free communication with the opening 22 and through that opening with the lower portion of the discharge pressure 25 chamber 24. The upper end of the duct 37 communicates through a metering opening 38 to the interior of the annular impeller 18 which has a longitudinal groove 39 milled in it at that location.

The discharge duct 40 in the plate 10 on the high pressure side of the cylinder 13 communicates with a valve chamber 41 on the outside of the plate 10. This housing contains a reed valve 42 adapted to close the duct 40 and an overhanging finger 43 which prevents excessive displacement of the valve from the plate 10. A discharge pipe 43 extends from the valve chamber 41 and is preferably formed in its lower portion into one or more convolutions to establish heat exchange between the hot compressed gases and the oil supply in the lower part of the discharge pressure chamber 24. The pipe 43 terminates in an open end in the upper portion of the discharge pressure chamber 24. Any oil entrained 45 with the gases falls into the lower part of the discharge pressure chamber 24. A gas lead off pipe 44 is connected to the upper end of the discharge pressure chamber 24. The pipe 44 supplies gas to condenser coils (not shown) which supply condensed refrigerant to a receiver (not shown) from which the liquefied refrigerant is supplied to the evaporator (not shown) of the refrigeration system as needed.

The vaporized refrigerant is returned to the 55

suction side of the cylinder by means of a pipe 46 which communicates with an intake port 47 which is covered and uncovered by the annular impeller 18 during each revolution of the shaft 16. The suction pipe 46 includes a check valve 48 which is adapted to open with flow towards the compressor.

A fine capillary tube 49 communicates with the pressure side of the cylinder 13, preferably at its lowest level as shown in Fig. 3. This capillary tube is wound into a coil 50 and its free end is located in the upper part of the discharge pressure chamber 24. The capillary tube 49 may suitably have an internal diameter of twenty-five one thousandths of an inch (0.0025 inch) and a length of about twelve inches. These dimensions are given by way of example only, since they may be varied considerably as long as the capillary serves as a high resistance liquid seal which is maintained during normal operation of the compressor and which blows out when the compressor stops, admitting gas under head pressure into the compressor chambers and into the intake pipe 46 so as to apply strong closing pressure on the check valve 48.

The operation is as follows: The operation of the motor causes the eccentric member 17 to rotate in counter-clockwise direction, as viewed in Fig. 3. The impeller member 18 is caused to execute a combined oscillatory and orbital movement around the cylinder 13. The clearances are such that the gas pumping depends upon lubricant sealing and high speed operation, for example, around two thousand revolutions per minute. At each revolution oil is fed through the duct 37 to the compressor. A part of the oil passes between the shaft 16 and bearing 14 into the chamber 34 from which it passes through the ducts 35, 36 into the annular chamber 28. A part of the oil passes through the bearing 15 into the chamber 28. The oil passes from the chamber 28 back into the cylinder 13 by duct 35. The oil in the cylinder 13 maintains a peripheral seal between the cylinder 13 and the annular impeller 18 and a certain amount of lubricant is expelled with the compressed gases back into the discharge pressure chamber 24 at each revolution. At each revolution a small plug of oil is forced into the capillary 49 and under normal operating conditions the capillary 49 is maintained substantially full of lubricant, the head pressure within the discharge pressure chamber 24 being unable to overcome the viscosity of the lubricant and blow it back into the cylinder 13 during the interval between impulses. During the operation of the motor, gases are drawn by the compressor from the conduit 46 past the check valve 48. These gases are compressed and delivered into the discharge pressure chamber 24 at high pressure.

When the motor is stopped the oil in the capillary tube 49 is no longer renewed and the gas under high pressure in the discharge pressure chamber 24 blows the oil therein into the cylinder 13. The high pressure gas passes readily into the cylinder 13 and displaces the oil film on the annular impeller 18 so that the gas passes freely to the suction side of the compressor. The result is that the compressor is substantially unloaded and is able to start operation again very readily. Furthermore, when the motor stops, the head pressure is applied to the check valve 48 so as positively to close that valve.

Although the invention has been described in connection with the specific details of a preferred embodiment thereof, it must be understood that such details are not intended to be limitative of the invention except in so far as is set forth in the accompanying claims.

I claim:

1. In combination, a gas compressor, a chamber enclosing said compressor, into which the compressor delivers, means for maintaining a supply of lubricant within the compressor, a valve in the outlet of said compressor, and open means establishing a high resistance liquid seal between said chamber and a low point of said compressor which is subjected regularly to compression.

2. In combination, a gas compressor having a suction inlet and a pressure outlet, a chamber enclosing said compressor, into which the outlet delivers, means for maintaining a supply of lubricant within the compressor, a check valve in said outlet, and an open capillary tube having a high liquid resistance communicating with said chamber and with a low point on the pressure side of the compressor and adapted to be supplied with successive slugs of lubricant during the operation of the compressor.

3. In combination, a gas compressor comprising a cylinder, a gyratory impeller having an orbital movement therein, a vane cooperating with the impeller separating the suction and pressure sides of said compressor, an inlet pipe communicating with the suction side of the compressor, a check valve in said inlet pipe, a discharge duct on the pressure side of the compressor, a discharge pressure chamber into which the duct discharges, a check valve in said duct, means for maintaining a supply of lubricant in said cylinder to maintain sealing relation between relatively moving parts in high speed operation, and a relatively long open restricted duct extending between the chamber and compressor, said duct being arranged to be supplied with sealing fluid during operation of the compressor, the liquid of the seal being blown out when the compressor stops to admit gas under pressure to the compressor and inlet pipe to unload the compressor and positively to close the check valve.

4. In combination, a gas compressor comprising a cylinder, a gyratory impeller having an orbital movement therein, a vane cooperating with the impeller separating the suction and pressure sides of said compressor, an inlet pipe communicating with the suction side of the compressor, a check valve in said inlet pipe, a discharge duct on the pressure side of the compressor, a discharge pressure chamber into which the duct discharges, a check valve in said duct, means for maintaining a supply of lubricant in said cylinder to maintain sealing relation between relatively moving parts in high speed operation, and a relatively long capillary tube communicating with the discharge pressure chamber and the pressure side of said compressor adapted to receive a slug of lubricant during each revolution of the compressor to maintain a high resistance liquid seal during high speed operation, the capillary tube being open whereby the liquid seal is blown out when the compressor stops to admit gas under pressure to the compressor and inlet pipe to unload the compressor and positively to close the check valve.

CARL W. ALBERTSON.
